7 Claims. (Cl. 179—171.5)

1

This invention relates generally to a variable-frequency oscillator system and particularly to an oscillator system which is useful in a frequency-modulation system. Specifically, the variable-frequency oscillator system of the invention is effective to provide a relatively large frequency change for a given control effect used to vary the frequency of the system.

In one type of prior art variable-frequency oscillator system, an oscillator is provided having a frequency which is determined by a resonant circuit used as the frequency-determining circuit for the oscillator, together with means for varying, in accordance with a modulation signal to be transmitted, the reactance of at least one element of the frequency-determining circuit, thereby to vary the frequency at which the circuit is resonant and in turn to change the operating frequency of the system. Arrangements of this type are effective to provide a relatively large modulation index. However, for some purposes, the sensitivity of the arrangement, or the ratio of the change of frequency of the oscillator to the change in the reactance element of the frequency-determining circuit, is not as large as is desirable.

Accordingly, it is an object of the invention to provide an improved variable-frequency oscillator system.

It is a still further object of the invention to provide a variable-frequency oscillator system which has an improved sensitivity characteristic.

It is also an object of the invention to provide a variable-frequency oscillator system, including an oscillator the frequency of which is determined by a resonant circuit and means for varying the reactance of at least one element of the resonant circuit to vary the frequency of the oscillator, in which there is provided a relatively large ratio between the per cent. frequency shift which is provided in the system for a given per cent. change of the reactance of the frequency-determining circuit.

In accordance with the invention, a variable-frequency oscillator system comprises an oscillator having a frequency-determining circuit portion including reactance elements of both types connected in parallel to form a first circuit resonant at a predetermined frequency, modulating means for varying the effective value of the reactance of at least one of the above-mentioned types in the frequency-determining circuit to vary the frequency of the oscillator from the above-mentioned predetermined frequency, and means including a second parallel-resonant circuit having reactance elements of both types and a resist-

2

ance element and coupled to the first resonant circuit with substantially critical coupling so as to modify the reactance of the first resonant circuit greatly to increase its sensitivity to the modulation effects of the modulating means.

For a better understanding of the present invention, together with other and further objects thereof, reference is had to the following description taken in connection with the accompanying drawing, and its scope will be pointed out in the appended claims.

The single figure of the drawing illustrates a variable-frequency oscillator system in accordance with the invention.

Referring now more particularly to the drawing, the circuit there shown comprises a variable-frequency oscillator system 10 including an oscillator comprising a vacuum tube 11. The system 10 includes a circuit comprising an inductor L₁ and a condenser C₁ effectively connected in parallel by means of coupling condensers 12, 13 and connected to the input electrodes of vacuum tube 11 through a coupling condenser 14 and a grid-leak resistor 15. In order to provide an oscillator having the circuit L₁, C₁ as the frequency-determining circuit, the output electrodes of tube 11 are inductively coupled thereto by means of an inductor 16 included in the anode circuit of tube 11 and inductively coupled to inductor L₁. The variable-frequency oscillator system 10 also includes a means for varying the effective value of the reactance of at least one type in the circuit L₁, C₁ to vary the frequency of the oscillator from its predetermined or normal frequency, as determined by the resonant frequency of circuit L₁, C₁. This last-named means includes a reactance tube 20 having its output electrodes coupled to circuit L₁, C₁ by means of a direct connection between the anode of tube 20 and the common terminal of inductor L₁ and condenser 13. Unidirectional operating potentials for tube 20 are provided by means of a source +B applied to the anode of tube 20 through a tap on inductor L₁ and to the screen electrode of tube 20 through a resistor 21. A self-biasing circuit is provided for tube 20 by means of a resistor 22 in the cathode circuit thereof, the resistor 22 being by-passed for alternating currents by a condenser 23. In order to cause tube 20 to function as a reactance tube, a phase-shifting network, including a series-connected resistor 24 and a condenser 25, is connected between the anode of tube 20 and ground. The change in reactance effectively provided in circuit L₁, C₁ by the tube 20 is

controlled by the application of a suitable control potential to the control grid of the tube.

The circuit so far described is conventional and, in order to cause the variable-frequency oscillator system to function in accordance with the teachings of the invention to provide a relatively high sensitivity, a second resonant circuit including an inductor L_2 , a condenser C_2 , and a resistor R_2 connected in series in a loop circuit is inductively coupled to circuit L_1 , C_1 by means of an inductive mutual coupling M between inductors L_1 and L_2 .

The variable-frequency oscillator system of the drawing is illustrated as used in a frequency-modulation signal transmitter and thus also includes a modulation-signal source 28 coupled to the input electrodes of tube 20 and an amplifier 29 having an input circuit coupled to the output electrodes of tube 11 and an output circuit connected to a balanced antenna system 31, 32.

Considering now the operation of the system illustrated in the drawing, and neglecting for the moment the function of resonant circuit L_2 , C_2 , R_2 , the arrangement disclosed comprises a conventional system in which tube 11 is included in an oscillator having as a frequency-determining circuit the resonant circuit L_1 , C_1 , the signal output thereof being amplified in unit 29 and applied to antenna system 31, 32 for radiation. Tube 20, due to the phase-shift network 24, 25, when conductive causes a current to flow through a portion of inductor L_1 which is of such phase as effectively to change the reactance in the loop circuit L_1 , 13, C_1 , 12, thereby to change the frequency of the oscillator system. The current which tube 20 provides in the circuit L_1 , C_1 is controlled by means of the modulation-signal source 28, thereby to vary the frequency of the oscillator in accordance with the modulation signal to provide a frequency-modulated signal for transmission.

In accordance with the invention, the circuit L_2 , C_2 , R_2 is inductively coupled to the circuit L_1 , C_1 and is tuned to substantially the same resonant frequency as that of circuit L_1 , C_1 in the absence of a control signal applied to the input electrodes of tube 20. The circuit L_2 , C_2 , R_2 has the effect of causing the system to have a greatly increased sensitivity; that is, a much greater change in frequency of the system is provided for a given change in the input control signal for reactance tube 20. In order to show more fully why this is true, the operation of the circuit is hereinafter analyzed under two conditions, namely, (1) the condition where M is zero, thereby effectively eliminating the circuit L_2 , C_2 , R_2 from consideration, and (2) the condition where M has a finite value, thereby to derive the conditions for optimum proportioning of the circuit in accordance with the invention.

The reactance of circuit L_1 , C_1 is given by the expression:

$$\omega L_1 - \frac{1}{\omega C_1} - \frac{(\omega M)^2 \left(\omega L_2 - \frac{1}{\omega C_2} \right)}{R_2^2 + \left(\omega L_2 - \frac{1}{\omega C_2} \right)^2} = f(\omega, L_1, C_1, M, L_2, C_2, R_2) \quad (1)$$

where

ω =Angular frequency in radians per second.

L_1 =Inductance value of inductor L_1 in henries.

L_2 =Inductance value of inductor L_2 in henries.

C_1 =Capacitance value of condenser C_1 in farads.

C_2 =Capacitance value of condenser C_2 in farads.

R_2 =Resistance value of resistor R_2 in ohms.

M =Mutual inductance in henries between circuit C_1 , L_1 and circuit C_2 , L_2 , R_2 .

Where $M=0$, the circuit L_2 , C_2 , R_2 has no effect on the operation of the circuit of Fig. 1 and, thus, under the assumed condition, the arrangement of Fig. 1 functions as the prior art device mentioned above. In order to bring out the advantages of the circuit of the present invention, the circuit operation will first be analyzed under the assumed condition so that the performance can be compared to that of the circuit of the invention. Therefore, in order to obtain the ratio of the change in frequency, under the assumed condition, to a change in the effective inductance of circuit C_1 , L_1 , consider the following:

At resonance

$$f(\omega) = 0 \quad (2)$$

$$20 \quad \omega_0 L_1 = \frac{1}{\omega_0 C_1} \quad (3)$$

and

$$25 \quad \omega_0 = \frac{1}{\sqrt{L_1 C_1}} \quad (4)$$

where the various symbols are as defined above and the subscript "0" indicates the static condition of the circuit of Fig. 1, that is, the condition under which reactance tube 20 is not effective to upset the normal reactance values of circuit L_1 , C_1 .

If the effective value of inductance in circuit C_1 , L_1 is changed by the action of tube 20, the change in $f(\omega)$ is:

$$35 \quad df(\omega) = \frac{\partial f(\omega)}{\partial \omega} \Big|_{\omega_0} d\omega_0 + \frac{\partial f(\omega)}{\partial L_1} \Big|_{\omega_0} dL_1. \quad (5)$$

However, under the new condition of circuit C_1 , L_1 , the expression $f(\omega)$ is still zero at resonance.

40 Therefore,

$$df(\omega) = 0 \quad (6)$$

And from Equation 5,

$$45 \quad \frac{d\omega_0}{dL_1} = - \frac{\partial f(\omega)}{\partial \omega} \Big|_{\omega_0} \quad (7)$$

But,

$$50 \quad \frac{\partial f(\omega)}{\partial L_1} = \omega \quad \text{or} \quad \frac{\partial f(\omega)}{\partial L_1} \Big|_{\omega_0} = \omega_0 \quad (8)$$

Also,

$$55 \quad \frac{\partial f(\omega)}{\partial \omega} = L_1 + \frac{1}{\omega^2 C_1} \quad \text{or} \quad \frac{\partial f(\omega)}{\partial \omega} \Big|_{\omega_0} = L_1 + \frac{1}{\omega_0^2 C_1} \quad (9)$$

And since

$$60 \quad L_1 = \frac{1}{\omega_0^2 C_1}$$

from Equation 3,

$$65 \quad \frac{d\omega_0}{dL_1} \Big|_{\omega_0} = 2L_1 \quad (10)$$

Therefore, from Equations 7, 8 and 10

$$68 \quad \frac{d\omega_0}{dL_1} = - \frac{\omega_0}{2L_1}$$

or

$$75 \quad \frac{d\omega_0/\omega_0}{dL_1/L_1} = - \frac{1}{2} \quad (11)$$

Equation 11 therefore gives the ratio of the change in resonant frequency of circuit C_1 , L_1 to the change in inductance of circuit C_1 , L_1 effected by the reactance tube 20 under the assumed condition.

Now the effect of the circuit L_2 , C_2 , R_2 on the arrangement of Fig. 1 will be similarly considered. Specifically, the circuit will be similarly analyzed under the condition when M is not zero.

Here, again, as in Equation 8

$$\frac{df(\omega)}{\partial L_1} = \omega \text{ or } \frac{df(\omega)}{\partial L_1} \Big|_{\omega=\omega_0} = \omega_0 \quad (12)$$

and

$$\begin{aligned} \frac{df(\omega)}{\partial \omega} &= L_1 + \frac{1}{\omega^2 C_1} - \frac{d}{d\omega} \left\{ (\omega M)^2 \left(\omega L_2 - \frac{1}{\omega C_2} \right) \left[R_2^2 + \left(\omega L_2 - \frac{1}{\omega C_2} \right)^2 \right]^{-1} \right\} = L_1 + \frac{1}{\omega^2 C_1} - \\ &2 \left(\omega L_2 - \frac{1}{\omega C_2} \right) \left[R_2^2 + \left(\omega L_2 - \frac{1}{\omega C_2} \right)^2 \right]^{-1} \omega M^2 - (\omega M)^2 \left[R_2^2 + \left(\omega L_2 - \frac{1}{\omega C_2} \right)^2 \right]^{-1} \left(L_2 + \frac{1}{\omega^2 C_2} \right) + \\ &2(\omega M)^2 \left(\omega L_2 - \frac{1}{\omega C_2} \right) \left(\omega L_2 - \frac{1}{\omega C_2} \right) \left(L_2 + \frac{1}{\omega^2 C_2} \right) \quad (13) \end{aligned}$$

Since, again,

$$L_1 = \frac{1}{\omega_0^2 C_1} \text{ and } L_2 = \frac{1}{\omega_0^2 C_2}$$

Equation 13 can be modified to obtain

$$\begin{aligned} \frac{df(\omega)}{\partial \omega} \Big|_{\omega=\omega_0} &= L_1 + \frac{1}{\omega_0^2 C_1} - \frac{(\omega_0 M)^2 \left(L_2 + \frac{1}{\omega_0^2 C_2} \right)}{R_2^2} \\ &= 2L_1 - \frac{2\omega_0^2 M^2 L_2}{R_2^2} \quad (14) \end{aligned}$$

By comparison to Equation 7,

$$\begin{aligned} \frac{d\omega_0}{dL_1} &= -\frac{df(\omega)}{\partial L_1} \Big|_{\omega=\omega_0} = \\ &-\frac{\omega_0}{2L_1 - \frac{2\omega_0^2 M^2 L_2}{R_2^2}} = -\frac{\omega_0}{2L_1 \left[1 - \frac{\omega_0^2 M^2 L_2}{L_1 R_2^2} \right]} \quad (15) \end{aligned}$$

or

$$\frac{d\omega_0/\omega_0}{dL_1/L_1} = \frac{-\frac{1}{2}}{\left[1 - \frac{\omega_0^2 M^2 L_2}{L_1 R_2^2} \right]} \quad (16)$$

Expression 16 therefore gives the ratio of the change in the resonant frequency of circuit C_1 , L_1 to the change in the inductance of the circuit C_1 , L_1 effected by the reactance tube 20 under the assumed condition. This ratio is caused to have a large value when the circuit of Fig. 1 is proportioned in accordance with the invention. Specifically, Expression 16 is infinite under the condition where

$$1 - \frac{\omega_0^2 M^2 L_2}{L_1 R_2^2} = 0 \quad (17)$$

or where

$$\left(\frac{\omega M}{R_2} \right)^2 = \frac{L_1}{L_2} \quad (18)$$

Actually it is not possible in a practical case to proportion the circuit so that Expression 16 is infinite. However, in accordance with the illustrated embodiment of the invention in which the second resonant circuit L_2 , C_2 , R_2 comprises series-connected elements, the circuit is proportioned so that

$$\left(\frac{\omega M}{R_2} \right)^2$$

is approximately equal to

$$\frac{L_1}{L_2}$$

and the condition in which they are equal will be referred to as the condition of "critical

coupling." It has been found that by approaching the critical coupling as nearly as possible the change in resonant frequency of the system for a given change of reactance in circuit L_1 , C_1 can be increased some four or five times.

It is to be understood that the arrangement of the invention is not limited to the particular oscillator circuit shown, but is applicable to any oscillator having a frequency-determining cir-

cuit, the reactance of which is controlled to vary the frequency of the oscillator, it being only necessary to provide in such a case an additional tuned circuit corresponding to L_2 , C_2 , R_2 coupled to the frequency-determining circuit of the oscillator with substantially critical coupling.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

35. What is claimed is:

1. A variable-frequency oscillator system comprising, an oscillator having a frequency-determining circuit portion including reactance elements of both types connected in parallel to form

40 a first circuit resonant at a predetermined frequency, modulating means for varying the effective value of the reactance of at least one of said types in said circuit to vary the frequency of said oscillator from said predetermined frequency, and means including a second parallel-resonant circuit having reactance elements of both types and a resistance element and coupled to said first resonant circuit with substantially critical coupling so as to modify the reactance of said first circuit greatly to increase its sensitivity to the modulation effects of said modulating means.

2. A variable-frequency oscillator system comprising, an oscillator having a frequency-determining circuit portion including reactance elements of both types connected in parallel to form a first circuit resonant at a predetermined frequency, modulating means for varying the effective value of the reactance of at least one of said types in said circuit to vary the frequency of said oscillator from said predetermined frequency, and means including a second circuit coupled to said first circuit with substantially critical coupling so as to modify the reactance of said first circuit greatly to increase its sensitivity to the modulation effects of said modulating means.

quency, modulating means for varying the effective value of the reactance of at least one of said types in said circuit to vary the frequency of said oscillator from said predetermined frequency, and means including a second parallel-resonant circuit having reactance elements of both types and a resistance element and inductively coupled to said first resonant circuit with substantially critical coupling so as to modify the reactance of said first circuit greatly to increase its sensitivity to the modulation effects of said modulating means.

4. A variable-frequency oscillator system comprising, an oscillator having a frequency-determining circuit portion including an inductor and a capacitor connected in parallel to form a first circuit resonant at a predetermined frequency, modulating means for effectively varying the value of the inductance in said circuit portion to vary the frequency of said oscillator from said predetermined frequency, and means including a second parallel-resonant circuit having reactance elements of both types and a resistance element and coupled to said first resonant circuit with substantially critical coupling so as to modify the reactance of said first circuit greatly to increase its sensitivity to the modulation effects of said modulating means.

5. A variable-frequency oscillator system comprising, an oscillator having a frequency-determining circuit portion including an inductance L_{10} and a capacitor connected in parallel to form a first circuit resonant at a predetermined frequency ω_0 , modulating means for varying the effective value of inductance in said circuit to vary the frequency of said oscillator from said predetermined frequency, and means including a second circuit having an inductance L_2 and appreciable series resistance R_2 and inductively coupled to said first circuit by a mutual inductance M , said second circuit having parallel resonance at said predetermined frequency and being proportioned so that

$$\left(\frac{\omega_0 M}{R_2}\right)^2$$

is substantially equal to

$$\frac{L_{10}}{L_2}$$

thereby to modify the reactance of said first circuit so as to increase greatly its sensitivity to the modulating effects of said modulating means.

6. A variable-frequency oscillator system comprising, an oscillator having a frequency-determining circuit portion including reactance elements of both types coupled in parallel to form a first circuit resonant at a predetermined frequency, modulating means including a reactance tube connected with said frequency determining circuit for varying the effective value of the reactance of at least one of said types in said circuit to vary the frequency of said oscillator from said predetermined frequency, and means including a second parallel-resonant circuit having reactance elements of both types and a resistance element and coupled to said first resonant circuit with substantially critical coupling so as to modify the reactance of said first circuit greatly to increase its sensitivity to the modulation effects of said modulating means.
- 5 7. A variable-frequency oscillator system comprising, a vacuum tube having input and output electrodes, a first circuit having parallel resonance at a predetermined frequency and including reactance elements of both types, means for connecting said input electrodes to said circuit and for inductively coupling said output electrodes to said circuit to form an oscillator in which said circuit is the frequency-determining circuit, modulating means for varying the effective value of the reactance of at least one of said types in said circuit to vary the frequency of said oscillator from said predetermined frequency, and means including a second parallel-resonant circuit having reactance elements of both types and a resistance element and coupled to said first resonant circuit with substantially critical coupling so as to modify the reactance of said first circuit greatly to increase its sensitivity to the modulation effects of said modulating means.
